[57] CLAIM

The ornamental design for a envelope, as shown and described.

DESCRIPTION

FIG. 1 is a front elevational view of an envelope showing my new design, with the broken lines indicating folding areas;

FIG. 2 is a rear elevational view thereof;

FIG. 3 is a front elevational view of a second embodiment thereof;

FIG. 4 is a rear elevational view thereof;

FIG. 5 is side elevational view thereof, with the opposite side being a mirror image of FIG. 1;

FIG. 6 is a side elevational view thereof, with the opposite side being a mirror image of FIG. 3;

FIG. 7 is a top plan view thereof, with the bottom being a mirror image of FIG. 1;

FIG. 8 is a top plan view thereof, with the bottom being a mirror image of FIG. 3;

FIG. 9 is a front elevational view of FIG. 1, with the envelope shown in closed condition; and,

FIG. 10 is a front elevational view of FIG. 3, with the envelope shown in closed condition.
